UNITED STATES PATENT OFFICE.

LEONARD J. JOHNSON, OF PHILADELPHIA, PENNSYLVANIA, ASSIGNOR TO HIMSELF AND
JAS. E. OWENS, OF PHILADELPHIA, PENNSYLVANIA.

MATCH-HOLDER.

Specification of Letters Patent No. 32,735, dated July 2, 1861.

To all whom it may concern:

Be it known that I, LEONARD J. JOHNSON, of the city and county of Philadelphia, State of Pennsylvania, have invented a new and useful Improvement in Pocket Match-Boxes; and I do hereby declare that the following is a full and exact description of the same, which I have prepared with a view to the obtaining of Letters Patent therefor, and

10 that the same is illustrated in the accompanying drawings, forming a part of this specification.

My invention consists in having a portable "box or case" similar to a visiting card case, provided internally with certain mechanism so formed and arranged that when the case or box is supplied with matches disposed within it in a certain way a match may, by raising or pulling up the "cap" or "lid" 15 be withdrawn from the box or case in an ignited state ready for use, without in any way exposing the matches within the box or case to dampness or accidental ignition; thereby affording safety in the carrying of 20 matches in the pocket and giving certainty 25 in the use of the match.

The principle upon which my improvement consists is this, that I construct on the interior part of the box or case a "holder" 30 for matches with two metallic sheet spring clamp plates of an elliptic form, intercepted by a rigid sheet plate, coated with emery on each side, or having sandpaper attached thereon by adhesive substances. The spring 35 clamps are intended to press the matches against the center plate and there retain them until withdrawn for use and to compel the match to rub on the emery or said paper (as the case may be) to ignite it, when 40 withdrawn from the holder, when matches are desired for use. When the matches are to be arranged in the holder, the holder is to be withdrawn or detached from the box or case (as shown in Figs. 2 and 3); the 45 matches are then placed invertedly in the holder at the ends. When the holder receives its complement of matches it is then forced back into the case at bottom, and there retained by the spring clamps so that it 50 forms a bottom flush with the sides of the box or case with a slight rim on one side for the fingers to withdraw or detach same from the box, when said box requires replenishing with matches. The box or case has a

hinged cap or lid, to preserve the matches 55 from exposure and dampness.

To enable others skilled in the manufacturing of "match boxes" to make and use my invention, I will proceed to describe its construction and operation, reference being 60 had to the annexed drawings making part hereof, and to the letters of reference marked thereon in which—

Figure 1 is a perspective view of the box or case, showing parts or ends of matches 65 in the holder with cap lifted. Figs. 2 and 3 are detached parts. Fig. 4 is a sectional view of the match holder.

A is the box or case with top R.

B is the match holder detached or withdrawn from A (Figs. 2 and 3) showing the elliptic spring clamps c, c with intercepting plate "d", coated with emery shown at "p". In the sectional view of the holder "B" Fig. "4" shows the manner matches 75 are arranged and the manner they are retained in the holder against the center plate "d" by the clamps c, c, as shall be herein-after more fully described.

Operation: When the box or case requires 80 matches withdraw the holder "B" from bottom of "A," then arrange the matches invertedly in at the ends of "B" between the clamps c, c and center plate "d." When said holder receives its complement of 85 matches replace or force the holder "B" in at the bottom of A again keeping of course the cap or top "R" down tight in its place. When the matches are desired for use pull up the top or lid "R" (in a 90 manner shown in Fig. 1) and take hold of a match between thumb and finger and withdraw same quickly and by the spring clamps c, c pressing the match tightly against the side of the center plate "d" compels the 95 match as it is being withdrawn, to rub against the emery on "d" thereby causing immediate ignition to the match on the moment it separates from the holder "B."

By this improvement, I produce a match 100 box for the pocket superior to any now in use either in point of safety, economy or cheapness and with a certainty of the matches igniting (if good ones) the moment they are separated from the box.

Having now fully described my invention, what I claim as new therein, and desire to secure by Letters Patent is—

The match holder B with elliptic sheet spring clamps c c for retaining the matches in place and compelling them to "rub" against a center plate "d", with emery or sandpaper or their equivalents attached thereon, for the purpose of causing ignition to the match when withdrawn from the same, the whole being arranged within and connected to the box or case "A" in a man-

ner substantially as, and for the purposes 10 specified.

In testimony whereof I hereunto set my hand.

LEONARD J. JOHNSON.
